Attorney

UNITED STATES PATENT OFFICE.

HARRY R. GEER, OF JOHNSTOWN, PENNSYLVANIA.

METAL-PIERCING.

1,321,096.

Specification of Letters Patent. Patented Nov. 11, 1919.

Application filed June 21, 1918. Serial No. 241,304.

To all whom it may concern:

Be it known that I, HARRY R. GEER, a citizen of the United States, residing in the city of Johnstown, in the county of Cambria and State of Pennsylvania, whose post-office address is Johnstown, Pennsylvania, have invented certain new and useful Improvements in Metal-Piercing; and I do hereby declare the following to be a full, clear, and 10 exact description, such as will enable others skilled in the art to which it appertains to make and use the same.

My invention relates to method and apparatus for piercing metals with particular reference to producing tubes, hollow articles, shells, etc. In order to simplify the description, I will confine the same herein to producing shells.

The operation of my invention, briefly 20 and generally stated, consists in taking a blank of metal, preferably heated, and which may be solid, cylindrical or of any other suitable form, placing the same in a casing or bushing, which is adapted to 25 round and support it on its sides, the bushing being closed at one end by a fixed block with its end or shape conforming to the finished shape of the product, while the bushing which immediately surrounds the sides 30 of the blank, has a temporary bottom support and is so held in the casing so as to be free to move longitudinally therein. After the blank is placed within the bushing with one end against the fixed block, a 35 piercing plunger is projected against the other end and into it and causes a depression or opening within the blank and the displacement or plastic flow of the side portions of the metal blank is, in part, opposite to the movement of the piercing tool. The intense pressure of the piercing tool against the material of the blank and of the latter against the sides of the bushing, causes a large amount of friction, particularly 45 against the bushing, due to this movement of the hot metal under intense pressure, thereby causing the speedy abrasion and wearing of the bushing, in case the same should be fixed, thereby speedily destroying 50 the bushing. By means of my invention, I obviate this difficulty by arranging and allowing the bushing to travel with the flow of the metal of the blank which is adjacent to it. When using the previous method of 55 cupping or piercing shell blanks or similar forgings within a cylindrical or other

shaped bushing provided with a solid or stationary bottom, this of necessity produces an upward flow of metal under high pressure between the piercing bar and the inner 60 walls of the bushing, thereby causing a severe cutting or abrasive action of the flowing metal, making it practically impossible to provide a bushing which will withstand this severe use, all of which is obviated by 65 my invention, in which the bushing is allowed to travel with the flow of the metal being operated upon.

I have discovered by actual trials that in using stationary bushings, there is a very 70 excessive pull due to the attempted movement of the bushing and its container, which is of such extent that it has broken hold-down bolts which are able to withstand a tensional stress of 600,000 pounds, the 75 pressure on the piercing plunger being about 1,400,000 pounds. In other words, the downward pressure of 700 tons on the piercing bar, causes an uplift of about 300 tons on the bushing, when it is attempted to hold the 80 same stationary, as customary. By the use of my method and movable bushing, a pressure of only 400 tons is required on the piercing bar, owing to the fact that the friction is reduced, due to the arrangement 85 of the bushing which is movable with the flow of metal, thus reducing all the strain on the hold-down bolts and allowing the operation to be performed with almost half the pressure and expense, and of course the 90 tool may be of much lighter and cheaper construction.

Having thus given a general description of my invention, I will now, in order to make the matter more clear, refer to the annexed 95 sheet of drawings forming part of this specification and in which like characters refer to like parts.

Figure 1 is a vertical cross sectional elevation of my apparatus with the piercing 100 tool in its upper position and the bushing in its lower position, ready to begin operation upon the blank;

Fig. 2 is a cross sectional elevation of the same apparatus with the piercing tool in its 105 lower position and the bushing in its upper position, after the forging is completed.

Referring now to the characters of reference on the drawings:

1 is the base of the apparatus, 2 an outer 110 casing which may be hollow cylindrical, or of other form, provided with the hold-down

base flanges 3 and the hold-down bolts 4, the opening within said casing being indicated as 5. A ledge or supporting surface 6 is provided at the upper part of the casing to receive the upper flange of the centering ring 26, which ring is adapted to be placed in position, as shown, or removed as desired, by any suitable means. This centering ring is provided with an opening 10 concentric with the bore of the shell or tube, and is adapted to guide the piercing tool concentrically so that the work may be exact. Recesses 7 are provided in the upper portion of the casing 2, to allow the introduction 15 of a forked tool, not shown, for the purpose of stripping the forging from the piercing bar in case they should adhere to each other. 8 is a tubular container adapted to fit within the casing 2, provided with water-circulating grooves 9, connected with the water inlet pipe 10 at one end and the water-outlet pipe 11 at the other end, these grooves being preferably made helical and continuous so that the water passes around the 20 outside of the bushing 14, for the purpose of keeping it cool and lengthening its life. An opening 15 is provided in the base 1, through which extends a plunger 16 which is adapted to be operated by any suitable 25 means not shown, for the purpose of pushing out or extracting the finished forging. 18 is a base block adapted to contact with and support the bushing 14 when in its lowered position. A bottom block or die 21 is arranged with its upper portion projecting within the die block 14, as illustrated, and having a lower portion 20, adapted to be normally seated upon the base, as shown. The upper portion of the die block 21 may 30 be made of any suitable form to correspond with that of the end of the forging. The blank, before piercing, is 23, the piercing bar 24, the blank or forging after being pierced is 25.

40 The operation of my apparatus is as follows:—The piercing bar being withdrawn, the centering ring is also withdrawn, the blank 23, which is previously heated, is dropped within the bushing 14, the centering ring is replaced in position, as illustrated, the piercing bar brought down with great force and penetrates within the blank, as illustrated in Fig. 2. It will be seen that the finished forging 25 is much longer than 45 the blank and that the metal as it extrudes backwardly between the piercing bar and the die must flow upwardly and carries with it the bushing 14 and attached parts which are free to move backwardly but 50 which cannot move forward at the beginning of the operation on account of the fixed support on which the forward end of the

blank initially rests. After this is accomplished, the piercing bar and centering ring are withdrawn, the extractor 16 is pushed 55 upwardly, which loosens the forging from the bushing and the forging is then lifted out by any suitable means.

Although I have described and illustrated my invention in considerable detail, I do 60 not wish to be limited to the exact and specific details thereof as shown and described but may use such modifications in, substitutions for, or equivalents thereof, as are embraced within the scope of my invention, or 65 as pointed out in the claims.

Having thus described my invention, what 70 I claim and desire to secure by Letters Patent is:—

1. The method of metal piercing which 75 consists in placing a substantially cylindrical or prismatic blank in an inclosing solid die or bushing, which die is initially supported at one end, then projecting a piercing bar against and into said blank while allowing 80 said bushing to move backwardly with the extrusion flow of the metal adjacent thereto while cooling means are applied to said bushing.

2. The method of metal piercing which 85 consists in placing a solid blank of cylindrical or prismatic form within a solid bushing, which bushing is initially supported at one end, the sides of said bushing being 90 adapted to contact with the sides of the blank, one end of said blank being firmly supported, then projecting a piercing bar against and into the other end of said blank while allowing the bushing to travel backwardly with the extrusion flow of the metal 95 of the blank adjacent thereto, while cooling means are applied to said bushing.

3. A metal piercing apparatus, comprising 100 a solid bushing or die adapted to surround the sides of a blank, provided with a support at one end, the bushing being held within a container adapted to fit around the exterior thereof and provided with cooling means, a piercing bar adapted to be projected into the other end of the blank and means for guiding said bushing and attached container while allowing them to move backwardly with the extrusion flow of the blank.

4. In a metal piercing apparatus, a guide 105 casing, a tubular container, provided with a bushing, slidably mounted therein, fluid cooling means for said bushing, a fixed support for one end of the bushing, and a piercing bar adapted to be projected into said bushing and withdrawn therefrom.

In witness whereof I hereunto affix my signature.

HARRY R. GEER.
